Des. 225,561
Patented Dec. 19, 1972

225,561

CABINET FOR A SUN LAMP

Thomas Mills, Lombard, Ill., assignor to Camrad
Precision Industries, Inc., Pelham, N.Y.

Filed Apr. 30, 1971, Ser. No. 139,030

Term of patent 14 years

Int. Cl. D26—99

U.S. Cl. D48—20

FIG. 1

FIG. 2

FIG. 4

FIG. 3

FIG. 5

FIG. 6

FIG. 1 is a left front perspective view of a cabinet for a sun lamp embodying my new design;

FIG. 2 is a top plan view of the cabinet shown in FIG. 1 on an enlarged scale;

FIG. 3 is a front elevational view thereof;

FIG. 4 is a right side elevational view thereof, the left side being substantially identical;

FIG. 5 is a rear elevational view thereof;

FIG. 6 is a bottom plan view thereof.

I claim:

The ornamental design for a cabinet for a sun lamp, as shown and described.
